(57) CLAIM

The ornamental design for a subcutaneous needle assembly, as shown and described.

DESCRIPTION

FIG. 1 is a top and right side perspective view of the subcutaneous needle assembly shown with its wings in the closed position and with a sleeve received over its needle and an elastic band over the wings, showing my new design, attached to a length of flexible plastic tubing shown in phantom;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top and right side perspective view of the subcutaneous needle assembly shown with the wings in an open position and disposed horizontally and with the elastic band received over the tubing;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a top and right side perspective view of the subcutaneous needle assembly with the wings shown in an open position and pressed together and the elastic band received over the tubing;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof;

FIG. 21 is a bottom plan view thereof;

FIG. 22 is a top and right side perspective view of the subcutaneous needle assembly shown with the wings in the closed position with its interlocking tabs pressed together and the elastic band received over the wings, but, without the sleeve received over the needle;

FIG. 23 is a front elevational view thereof;

FIG. 24 is a rear elevational view thereof;

FIG. 25 is a right side elevational view thereof;

FIG. 26 is a left side elevational view thereof;

FIG. 27 is a top plan view thereof; and,

FIG. 28 is a bottom plan view thereof;

The broken line is included for the purpose of illustrating the tubing portion of the subcutaneous needle assembly and forms no part of the claimed design.
